UNITED STATES PATENT OFFICE.

FREDERICK R. HIRSH, OF NEW YORK, N. Y., ASSIGNOR TO THE YALE & TOWNE MANUFACTURING COMPANY, OF STAMFORD, CONNECTICUT.

DESIGN FOR A PADLOCK-CASE.

SPECIFICATION forming part of Design No. 25,174, dated February 18, 1896.

Application filed December 11, 1895. Serial No. 571,832. Term of patent 7 years.

To all whom it may concern:

Be it known that I, FREDERICK R. HIRSH, a citizen of the United States, and a resident of New York, in the county and State of New York, have invented and produced a new and original Design for a Padlock-Case, of which the following is a specification, reference being had to the accompanying drawings, forming a part thereof.

10 Figure 1 is a front view of a padlock-case showing my design. Fig. 2 is a central vertical longitudinal section of the padlock-case shown in Fig. 1.

The leading feature of my design consists 15 in the padlock-case having the configuration shown and the representation of a lion's head on the body thereof.

The front of the body of the padlock-case, as shown in Fig. 1, has an elevated or stamped-up portion representing the head of a lion, ²⁰ and, as shown in Fig. 2, the back of the case may be similarly elevated or stamped up to represent the head of a lion.

Having thus described my invention, the following is what I claim as new therein and ²⁵ desire to secure by Design Letters Patent:

The design for a padlock-case, substantially as herein shown and described.

FREDERICK R. HIRSH.
